Atty.

UNITED STATES PATENT OFFICE

2,575,222

FAUCET SPRAY ATTACHMENT

Stanley Isenberg, Chicago, Ill.

Application May 6, 1946, Serial No. 667,607

1 Claim. (Cl. 299—145)

1

This invention relates to faucet attachments, and more particularly to a molded faucet attachment of rubber or the like, which is adapted to provide, selectively, a spray or a full stream of water.

It is one of the objects of the present invention to provide a simple, economical and efficient faucet attachment through which water may be selectively discharged in the form of a spray or in the form of a full stream, and which attachment may be turned angularly to direct the stream or spray in different directions as desired.

It is a further object of the present invention to provide such a faucet attachment which may be easily molded without requiring the use of a mold which leaves a parting line extending lengthwise of the attachment. This result is accomplished by making the attachment of such a shape that its cross sectional diameter diminishes from a maximum at one end of the attachment to a minimum at the opposite end of the attachment and where none of the intermediate portions of the length of the attachment is of a diameter appreciably less than that of both ends of the attachment. By this arrangement it is possible to mold the article and then extract the molded rubber article by pulling the same through the mold. The mold, therefore, does not have to be parted on a line extending lengthwise of the attachment in order to permit removal of the molded article from the mold.

The present invention contemplates the use of a spray plate having a perforated closure disc overlying a central opening in the plate, which closure plate is selectively movable to and from a position overlying the central opening in the plate so as to provide, selectively, a spray or a full stream of water. It is one of the objects of the present invention to provide simple stop means for the movable closure which will determine the alternate positions of the closure. The perforated closure is mounted on an arm that is pivoted on the spray plate. In one extreme position the perforated closure engages the side wall of the rubber faucet attachment which acts as a stop limiting the movement of the spray plate in that direction. The arm which carries said closure has a projection integral therewith which projection also engages the inner wall of the rubber attachment when the closure is in its central or spraying position, thus limiting the movement of the closure.

The attainment of the above and further objects of the present invention will be apparent from the following specification taken in con-

2

junction with the accompanying drawing forming a part thereof.

In the drawing:

Figure 1 is a side view of a faucet attachment 5 of the present invention shown as attached to a faucet;

Figure 2 is a longitudinal sectional view through the faucet attachment of the present invention; and

Figure 3 is a sectional view taken along the line 3—3 of Figure 2.

Reference may now be had more particularly to the drawing wherein like reference numerals designate like parts throughout. At 1 is shown 15 the end of a standard domestic type faucet to which the applicant's faucet attachment 2 is secured. The faucet attachment is made of molded rubber and is quite resilient. It is circular in cross section throughout. It consists of a cylindrical neck 3 having a plurality of inwardly extending annular flanges 4, 5 and 6 for gripping the end of the faucet. Each of the flanges extends downwardly as well as inwardly, the angle of inclination being substantially the same in 20 each case. The top flange 4 is of somewhat greater thickness than are the flanges 5 and 6 and extends inwardly a larger amount, so that the faucet receiving opening formed at the top flange 4 is smaller than the faucet receiving openings in the flanges 5 and 6, whereby the top flange 4 grips the faucet more tightly than do the other flanges, thereby insuring against leakage of water outwardly through the top of the attachment between that flange and the faucet. The downward inclination of the flanges facilitates 25 positioning of the attachment onto the faucet and prevents accidental removal thereof from the faucet.

The lower end of the cylindrical neck 3 has an 30 integrally formed outwardly flared skirt 8 which has a short inwardly projecting flange 10, constituting an integral part of the rest of the skirt, for receiving and holding the spray plate in a manner to be more fully set forth as this description proceeds. Also integrally formed with the cylindrical neck 3 and the skirt 8 is an inverted frusto conical portion 11 which serves as a funnel to guide the water towards the central opening in the spray plate, as will be more fully set forth as this description proceeds. At the juncture between the top of the frusto conical portion 11 and the inner surface of the cylinder 3 there is formed 35 a groove for receiving and holding a metal gauze filter screen 12. The inner surface of the cylinder neck 3 has a large number of small inwardly

extending circular flanges 15 which extend around the entire inside surface of the neck.

A circular spray plate 17 is positioned within the skirt 8 and rests on the peripheral flange 10. It is positioned by stretching the rubber of the skirt 8 an amount sufficient to permit the peripheral flange thereof to pass over and around the periphery of the spray plate 17. Pivotal secured to the top side of the spray plate 17 is a flat sheet metal arm 18 which has at one end thereof a perforated disc 19 and at the other end a short arcuate stop arm 20. The arm 18 is pivoted to the disc 17 by means of a short rivet 21 that passes through the arm 18 and through a slightly oversized rivet hole in the plate 17, and which rivet has secured to the lower end thereof an operating handle 22. The arm 18 is non-rotatable with respect to the rivet, and the handle 22 is also non-rotatable with respect to the rivet so that by turning of the handle 22 the rivet 21 is turned, which turns the arm 18. When the arm 18 is in the position illustrated in Figure 3 the disc 19 overlies a central hole 24 in the spray plate 17. The projecting stop arm 20 bears against the inner periphery of the skirt 8 thus limiting the amount of turning of the arm 18 in one direction. When the arm is turning in the opposite direction to move the perforated disc 19 away from the opening 24 in the plate 17 the opening 24 is uncovered. The disc 19 can move until it reaches the position indicated in dotted lines in Figure 3, where it is in engagement with the inner periphery of the skirt 8. It is thus apparent that the inner periphery of the skirt 8 acts as a limiting stop for the movement of the arm 18 in each direction.

The neck 3 of the spray attachment is quite long, being of a length approximately twice its diameter. Because of the length of the neck the spray attachment of the present invention, when it is attached to a faucet, may be twisted or flexed from the position illustrated in full lines in Figure 1 through a large angle. When this is done the circular flanges 15 on the interior of the cylindrical neck 3 determine the direction of bending or folding of the circular neck and assure that the fold shall take place between adjacent flanges 15. This increases the life of the spray attachment.

It is to be noted that the perforated disc 19 has comparatively few holes therein. When the disc is in position overlying the opening 24 water is guided down the funnel 11 where it impacts against the disc 19. It is also to be noted that the bottom of the funnel portion 11 terminates a distance above the perforated disc 19. Water therefore flows radially outwardly in the space between the disc 19 and the bottom of the funnel 11, filling the bottom of the skirt 8 and discharging through the perforated holes in the plate 17. When the disc 19 is moved to its opposite extreme position, as illustrated in dotted lines in Figure 3, the opening 24 is uncovered. The funnel 11 directs water towards the center of the opening 24 so that all of the water emerges from the funnel as a stream which passes in stream formation through the opening 24.

The rubber spray attachment of the present invention is of a maximum diameter at the lower end thereof. In passing upwardly from the skirt 8 along the outer surface of the cylindrical neck 3 to the end of the neck there never is a substantial increase in diameter. It is therefore possible to mold this article by means of a mold which has a cylindrical opening for forming the

outer surface of the neck 3, in which cylindrical opening there is positioned a core for forming the inner surface. After the article has been molded it may be removed from the mold by pulling the same lengthwise through the mold, the skirt 8, of course, emerging first. As a result the molding is quite simple, and it is not necessary to have a mold which embraces the cylindrical neck in two parts that are parted along the line extending lengthwise of the neck, such as would be necessary if the top of the neck had an enlarged head thereon. The cost of molding this attachment with a long neck and devoid of an enlarged head at the top of the neck is substantially less than would be the case if an enlarged head were provided at the top of the neck.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

25 A faucet attachment comprising a rubber casing having a depending outwardly flared annular skirt and a spray plate unit encircled by said skirt, said unit comprising a plate with a large central opening and a plurality of small spray 30 openings surrounding the large central opening, valve means including a sheet metal arm pivoted on the plate adjacent the periphery thereof for sliding movement across the plate and said arm having as an integral part thereof a perforated 35 disc portion adapted to overlie the central plate opening when the arm is in one position and movable to uncover the central opening when the arm is in its alternate position, said disc in its alternate position engaging the annular skirt 40 which limits the extent of movement of the valve disc in one direction, said sheet metal arm having as an integral part thereof a limiting stop projecting therefrom adjacent the pivot of the disc, said stop having an arcuate edge of an arcuate 45 length greater than the width of the arm and centered at the center of the disc and of a radius equal to that of the circular plate so that the entire arcuate edge engages the skirt of the casing when the disc overlies the central opening thus limiting the extent of turning of the disc 50 from its alternate position back to its first mentioned position, said limiting stop when in its stopping position extending from the disc pivot substantially along the periphery of the plate 55 and outside of the region of the spray openings in the plate.
